UNITED STATES PATENT OFFICE.

HERBERT F. OBERFELL, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

PANELED STRUCTURE.

Application filed June 11, 1925. Serial No. 38,310.

This invention relates in general to panel structure, more specifically the invention relates to an improved construction of paneled structures, such as doors, windows, show cases and the like, which permits of ease in manufacturing and assembly with a consequent reduction in manufacturing costs.

An object of the invention is the provision of a paneled structure wherein the weight of the upper panels is removed from the lower panels and supported on special supporting members.

Another object of my invention is to provide a mounting for the glass panels of a structure, which can be easily disassembled whenever it is necessary to replace a broken glass.

Further objects of my invention not specifically referred to here will be apparent from the specification and claims which follow.

The drawings comprising Figs. 1, 2, and 3 show sufficient details of a door constructed in accordance with the objects of my invention, to enable a clear understanding of the invention. Fig. 3 shows a portion of the top, middle, and bottom sections of a completely assembled door. Fig. 1 shows the top, middle and bottom sections of a door with a part of the outer members cut away to disclose the internal construction. Fig. 2 is a cross section view of Fig. 1 taken along the line AA before the outside members were broken away.

In an automatic telephone system of the well-known Strowger type, it has been found expedient to provide a dust proof housing for certain of the switches, to protect the switches from dust, dampness, and mechanical injury due to some object falling against them. The switches so protected are for example, the plunger type primary or secondary line switches. An example of an installation of this kind may be seen in Fig. 95, on page 113 of the second edition of "Automatic Telephony" by Smith and Campbell. In this figure it will be noticed that in the foreground are five line switchboards enclosed in a glass and steel case which completely sur-

rounds them. End views of such a case may be seen to the right or left of the foreground section. It is to the construction of the doors comprising such a case, for example, that this invention is directed.

In the construction of the doors pictured in the above Figure 95 the main frame of the door was made up of four pieces of channel iron which were welded together at the corners. The cross bars separating the panels of the door were made of T-shaped sections which were welded to the door stiles. The glass panels were set in U shaped rubber sections and clamped into the door frame by wooden strips which were held to the door by machine screws. While this construction gave a good sturdy door that was fairly light, its manufacturing cost was rather high, and accordingly the door of my invention was made to improve upon its predecessor and to reduce this manufacturing cost.

In the door of my invention I have replaced the angle iron frame by a channel iron which has approximately a $1\frac{1}{2}$ " web and 1" flange. The stiles 1, bottom cross piece 3 and the top cross piece 2 are made of this channel iron and are mitered and drilled to fit as shown in the drawing. The cross bars 4 separating the glass sections, are made of H sections of such dimensions as to permit their sliding freely in the channel of the door frame. The glass or metal panels such as 6 and 7 are supported in wooden strips which fit in the channel of the frame and into which the panels are fitted. This arrangement replaces the rubber channel and wooden strips of the old door and accomplishes the same purpose, that is preventing the panel from coming in contact with the metal frame. I have by incorporating the objects of my invention produced a door which is equally as sturdy as its predecessor, is of more pleasing appearance, and is cheaper to manufacture.

In assembling this door frame the stiles 1 and the bottom cross piece 3 are welded together forming a U shaped member with the groove of the channels on the inside of the U. The top cross piece 2 is attached to

this **U** by means of the corner braces 8 which are held in place by machine screws substantially as shown in the drawing.

In assembling this door the bottom wooden grooved strip 11 is slipped into the channel at the bottom of the **U** and the side wooden strips 10 are slipped into the channels of the stiles adjacent thereto. The glass or metal panel 7 is then slipped into the grooves formed by these three wooden strips. The **H** shaped cross section 4 is then fitted with the felt washers 5 in the channels of the **H** and slid into the channels of the stiles down onto the panel 7 and the side supporting wooden strips 10, to complete the panel of the door. By this arrangement the panel 7 is prevented from coming in contact with the frame members 1 and 3 by means of the wooden strips 10 and 11, and is prevented from coming in contact with the cross member 4 by means of the felt washer 5. The side strips 10 are of such a length as to support the cross member 4 so that its weight and the weight of the panels immediately above it are supported by the wooden strips rather than by the panel member 7.

Other panels are added to the door in the similar manner, the last panel using a stile wooden strip 9 and a cross member wooden strip 12 which differ from the other strips in that they are formed to fit around the corner braces 8. When the last panel is in place the top cross member 2 is placed and the machine screws tightened into the corner brace and the door is completed, ready to receive the hinges and door pulls which may be of any well known type attached in the regular manner.

In practice it is not necessary to provide right and left hand doors in the formation of a case such as shown in Fig. 95 of the above reference. The door of my invention may be equipped with hinges and door pulls which are so located as to be symmetrical, thereby enabling the door to be turned end for end to form a right or left hand door. On one of the doors, a left hand door for example, the welded section of the frame will appear at the bottom, and on the other door, that is the right hand door, the welded section will appear at the top. The construction of the doors is such that in either case the weight of the cross members and panels are supported by the side strips 9 and 10.

In the event that one of the glass sections becomes broken and has to be replaced, the door is disassembled by removing the machine screw 13 which loosens the corner brace and end section 2 which can then be removed, the panels and side strips are removed down to the broken panel which is then replaced, and the door reassembled in the same manner as already described.

Having thus described my invention what

I consider new and desire to have protected by Letters Patent is pointed out in the appended claims.

What is claimed is:

1. A paneled structure comprising a channel frame, panel members, grooved strips which fit into said frame channels and which support said panels, panel separating cross members which are slipped into said channels, and which rest on certain of said strips and over said panels, said strips and cross members holding each other in place in said channel frame the members of which form the sole means of holding said structure together. 70

2. A paneled structure comprising a rectangular frame composed of channeled sections, three sides of said frame being permanently fixed together, the fourth side being detachable therefrom, panels for said structure, supporting strips for said panels, said strips fitting into the channels of said frame, and panel separating members which fit into said frame channels, rest on certain of said supporting strips and slip over said panels, the weight of the bottom one of said panels being supported solely by one of said strips and the weight of the other panels being supported by said separating members which are in turn supported by said strips, the various members of said structure being held in their respective places solely by the other members and said channeled frame. 85

3. In a paneled structure, a channel iron rectangular frame, three sides of which are welded together, the fourth side being held thereon by screws, glass or metallic panels for said structure, removable wooden strips fitting into the channel of said frame, said strips containing grooves into which said panels fit, a panel separating member of **H** shaped cross section which slides into the channel of said frame, a felt strip which fits into the groove in said **H** section, said felt and wooden strips cooperating to prevent the panels from coming in contact with said metal frame work and said wooden strips supporting said panels and **H** section. 100

4. A paneled structure consisting of a steel frame having a base and a pair of uprights each part having a channel registering with the channels of the others, means comprising a series of removable units for supporting panels in said frame, said units including side supports and cross bars each recessed in register to retain a panel, and each unit supported in the frame solely by the other units. 115

5. A paneled structure consisting of a steel frame having a base and a pair of uprights each part having a channel registering with the channels of the others, means comprising a series of removable units for supporting panels in said frame, said units including side supports and cross bars each 120

recessed in register to retain a panel, and each unit supported in the frame solely by the other units, said side supports being all shorter than the panel supported thereby and acting as supports for the cross bar, and each cross bar supporting the side supports of the adjacent panel.

6. A rectangular paneled structure comprising a channeled frame one end and two sides of which are permanently fixed together, and the other end being removably attached thereto, panels for said structure, grooved supports for said panels the supports for the first panel being removably fitted in the channels of said fixed end and sides adjacent thereto and the panel slid into the grooves of the supports, H section separating members, one of which is slid into said side channels onto said side supports and over said panel to form a top therefor and a bottom for the next panel, the sup-

ports and separating members of the next and other panels being similarly inserted, the removable end of said frame forming a top for the last panel and a means for holding the various parts of the assembly in their respective positions.

7. A frame for a paneled structure comprising base and side members, and means for building up a series of interchangeable panels therein consisting of grooved strips slightly shorter than the panels they support and cross members, said structure built up and assembled in said frame in units each comprising a base and a pair of side supports and each unit acting as the sole vertical support for the next unit, said units being all interchangeable and removable.

In witness whereof, I hereunto subscribe my name this 6th day of June, A. D. 1925.

HERBERT F. OBERGFELL.
